SWITCH PLATE FOR ELECTRIC SWITCH

Lawrence P. Mellyn, Glocester, R.I., assignor to General Electric Company, a corporation of New York

Filed Oct. 30, 1968, Ser. No. 14,225

Term of patent 14 years

Int. Cl. D8—03

U.S. Cl. D8—181

Fig. 1.

Fig. 4.

Fig. 2.

Fig. 3.

FIGURE 1 is a front perspective view of a switch plate for electric switch embodying my new design;

FIGURE 2 is a front elevational view thereof;

FIGURE 3 is a bottom plan view thereof;

FIGURE 4 is a side elevational view thereof.
The dominant features of my design reside in the portions shown in full lines.

I claim:

The ornamental design for a switch plate for electric switch, as shown and described.
